BROODER FOR CHICKS

Donald B. Tolley and Dewey H. Hill, Macomb, Ill.,
assignors to Globe American Corporation, Ko-
komo, Ind., a corporation

Original application March 11, 1936, Serial No.
68,176. Divided and this application Septem-
ber 26, 1936, Serial No. 102,735

2 Claims. (Cl. 237—14)

This invention relates to a brooder for chicks and the present application is a division of application Serial No. 68,176, filed March 11, 1936, in which certain features of the invention disclosed herein, but not claimed, are specifically 5 claimed.

Other features of the invention disclosed but not claimed herein are claimed in co-pending application Serial No. 103,632, filed October 2, 10 1936.

In chick brooders using an oil burner, it has been the practice to provide a central heating drum having an oil burner in the bottom thereof with which a feed pipe and an overflow pipe 15 communicate. The drum is supported above the floor by suitable legs and is surrounded by an outwardly and downwardly extending canopy under which the chicks may assemble for warmth.

It is the object of this invention to provide a 20 brooder of simplified construction but of greater efficiency both as to heating qualities and heat control, as well as assembly.

One feature of the invention resides in the burner mounted in the drum, and particularly the 25 employment of a heat deflector and drip pan below the bottom of the drum and burner. It has been found desirable to interpose a shield or deflector between the bottom of the heater and the floor upon which the chicks are brooded to protect the floor and chicks from excess heat. 30 It is also found desirable to provide a construction whereby ready access is had to the inlet and outlet oil passages connected to the burner mounted in the bottom of the heating drum and to so arrange the oil inlet pipe that it may be 35 shielded against the intense heat thrown off by the bottom of the heater drum. This construction, therefore, provides for positioning the oil inlet pipe below the shield or deflector in a position directly under the burner before directing 40 it upward to the burner inlet. It is also found desirable to perfect a construction wherein any oil overflow from the burner may be harmlessly led away. This is accomplished by utilizing the 45 shield or deflector as a drip pan to receive any overflow of oil from the burner and direct it into a cup mounted below the shield. In providing for the above construction and the ensuing advantages, the burner is formed with nipples suitably arranged below the shield so that the inlet 50 and outlet pipes may be conveniently connected and disconnected therewith.

Other objects and features of the invention will be understood from the accompanying drawing 55 and the following description and claims:

Fig. 1 is a central vertical section through the brooder with parts thereof shown in elevation.

Fig. 2 is a section taken on the line 2—2 of Fig. 1.

Fig. 3 is a section taken on the line 3—3 of 5 Fig. 1.

In the drawing, there is illustrated a brooder having an annular drum heater provided with peripheral side walls 10, a bottom 11 and a top 12. The heating drum is supported above the 10 floor by legs 13 and is surrounded by a downwardly and outwardly extending canopy 14. The canopy is supported by an annular ring 15 which is apertured at 16 to receive a hinge member 17. Thus the canopy may be swung about the hinge 15 member 17 to a raised position for inspection, cleaning, etc.

At what may be termed the "rear" of the drum, and positioned adjacent the hinged member 17 in the top 12, there is a flue outlet 18 to which the usual flue 19 is attached. Positioned within the heater there is provided a baffle plate 20 which is formed with a central opening and a plurality of apertures 21 formed about the outer edge adjacent the wall of the heating drum. Said apertures are particularly positioned to control and direct the passage of heated gases from the burner to the flue. For this purpose, the apertures 21 are particularly spaced about the baffle with respect to the flue. 30

In order to prevent the heated gases from passing directly upward from the burner to the top of the drum and out the flue, and to provide an insulating dead air space centrally of the drum and cause the gases to travel only through the 35 apertures particularly positioned for that purpose in the baffle, there is provided an inner drum. Said inner drum has a bottom 22, a peripheral wall 23 and a top 24. It is adapted to be positioned within the heating drum and removable therefrom by mounting within the opening left in the top 12 of the drum and the opening in the baffle 20. Said inner drum is provided with central openings in both the bottom and top, but the wall 23 thereof entirely closes off any 45 passageway to the flue 19 other than through the apertures 21 in the baffle. The central opening is provided in the inner drum to permit removal therethrough of the flame spreader 25 by means of a cleaner rod 26 and cleaner pipe 27. 50

A top lid 28 is mounted upon the cleaner rod for closing the central opening in the top 24 of the inner drum. Thus, the heating drum is covered by its immovable top 12, the top 24 of the inner drum and the lid 28. By reason of the inner 55

drum construction, ready access can be obtained to the burner for cleaning the same through removal of the lid 28. Removal of the inner drum allows access to be had to the entire inner surface of the heating drum for cleaning and inspection. At the same time, the inner drum provides a dead air space since the heated gases passing through the central opening therein are trapped within the walls 22, 23, 24 and 28, and, while some heat is lost due to conduction, no appreciable flow of heated gases occurs. Consequently, the entrapped gases in the inner drum will serve somewhat as an insulating medium to prevent convection of excessive heat from the top of the heating drum.

The burner body comprises a casting secured to and supported upon the bottom 11 of the heating drum. Said casting comprises an outer ring 30 which supports an inner annular oil cup 31 by spaced ribs 32. A burner ring 33 is seated within the annular oil cup 31 above which the flame spreader 25 is positioned. On one side of the oil cup there is cast therewith a pipe coupling 34 to which there is connected an overflow cup 35 through a short pipe 36. The overflow cup has an offset enlargement which is connected with the overflow pipe 37, the short pipe 36 being directly connected through the overflow cup, but not communicating therewith, with an inlet pipe 38. The burner above described is substantially shown and illustrated in Patent No. 1,982,303, issued November 27, 1934 on an application of Dewey H. Hill.

Supported by the legs 13 below the bottom 11 of the burner drum, there is a combined heat deflector or shield and drip pan 39, said shield being spaced from the bottom 11 to provide an insulating dead air space therebetween and prevent the space below the burner under which the chicks 40 may huddle from being excessively heated by the bottom 11 of the burner drum. Substantially centrally of the shield but slightly off center, there is a concave portion 40 which serves as a drip pan and through the center of which the 45 short pipe 36 projects, said concave portion being so positioned with respect to the burner as to catch any overflow of oil therefrom and cause it to enter the overflow cup 35 so as to escape through the overflow pipe 37. By reason of this 50 construction, the inlet pipe 38 may be conveniently connected to and disconnected from the overflow cup as well as from the overflow pipe, such connections and disconnections being made below the burner drum and shield 39. This arrangement 55 is most desirable for convenience in connecting and disconnecting the brooder from the oil pipe connections.

In order that the desired temperature may be maintained within the brooder canopy, the oil 60 inlet pipe 38 is caused to extend upwardly through

an aperture 41 in that side of the canopy opposite the flue. Secured on the inner side of the upstanding portion of the inlet pipe there is provided a bracket 42 supporting thermostatic wafer 43, the bracket and wafer extending well within the outer periphery of the canopy. Mounted upon the upper end of the pipe and exteriorly of the canopy there is a control valve mechanism comprising a sight feed 44, a shut-off valve 45 and a thermostatically operated valve rod 46, the rod 46 being actuated by a thermostatic control lever 47 which is in turn actuated by the thermostatically actuated rod 48, said rod being adjustable with respect to the lever 47 by means of the screw threads and thumb nut 49. The valve lever is shielded by a cover 50 and its control is limited by maximum and minimum set screws 51. Through this means, the temperature of the air within the canopy may be automatically controlled through a thermostatically controlled oil valve conveniently positioned exteriorly of the canopy. Such adjustments and observations may be made at a convenient outside position for control of the heat interiorly of the canopy.

The invention claimed is:

1. An oil burning heating drum for brooders including an oil burner mounted centrally of the bottom of the drum, a shield below said bottom supported in spaced relation thereto and extending throughout substantially the entire area thereof for insulating the air therebelow from said bottom, said shield having an apertured depression formed therein immediately below said burner for receiving oil overflow therefrom, and an oil overflow cup depending from said burner about 35 said aperture for receiving oil from the depression in the shield for discharge from the heating drum.
2. An oil burning heating drum for brooders, including an oil burner mounted substantially centrally of the bottom of the drum, a shield below said bottom supported in spaced relation thereto and extending throughout substantially the entire area thereof for insulating the air therebelow from the bottom, said shield being provided with an apertured depression for receiving 45 oil overflow from said burner, a depending fitting supported by said burner under said shield and having a connection extending through the aperture therein, said fitting having an oil overflow cup for receiving oil from the burner and shield through said aperture, a discharge pipe 50 removably connected with said overflow cup extending below said shield from the heating drum and an oil feed pipe removably connected with said fitting below said shield for feeding oil 55 through said fitting and aperture in the shield to the burner.

DONALD B. TOLLEY.
